LIGHT-SENSITIVE MATERIAL

Walter Michaelis, Brussels-Forest, Belgium, assignor, by mesne assignments, to Chromogen, Incorporated, a corporation of Nevada

Application January 8, 1940, Serial No. 312,983
In Great Britain January 10, 1939

5 Claims. (Cl. 95—2)

The present invention relates to a process for producing photographic dye images by local removal of the dye from homogeneously colored layers that contain photographic silver images produced in silver halide emulsion layers colored complementarily to the sensitivity of the layer. The process comprises the local removal of the dye from a multilayer material, the layers of which are carried by a transparent support, at least one layer containing identical silver images produced by exposure of the layer from both sides thereof.

The invention further relates to a multilayer light-sensitive material comprising several colored light-sensitive layers for carrying out the process and for producing multicolor photographs by direct exposure in an appropriate camera or by printing.

A great number of methods have already been described for producing color-photographic materials with a number of emulsion layers dyed to different colors with dyes used in the production of the final color image, the emulsion layers being sensitive to light of different colors. The individual layers are either sensitized for light rays that are absorbed by the color with which the layer is dyed, or the layers are sensitized for light rays of a color not absorbed by the color of the layer. Materials of the latter type do not permit one to obtain color-photographs true to nature from the material exposed in the camera. On the other hand, the materials of the first-mentioned group when treated with the dye-destroying solutions that destroy the dyes where silver is present have hitherto yielded pictures that are not satisfactory, the reasons being as follows:

The dye present in the layer absorbs the light rays of the color for which the emulsion has been sensitized and if the dye possesses the concentration requisite for the production of intensely colored pictures, its absorption limits the exposure on the surface of the layer. The pictures obtained are flat and of unsatisfactory appearance.

In the accompanying drawing I have shown a diagrammatic cross sectional illustration of a typical multilayer material made in accordance with the present invention.

In carrying out the present invention a multilayer material such as shown in the drawing is used, the layers of which are dyed complementary to the sensitivity of the layer and the material is adapted to be exposed from both sides. By permitting the light to penetrate from both

sides into such a layer (which is dyed with a concentration sufficient to produce an intensely colored image), one can produce therein two exactly registered images that reinforce each other and permit one to process the layer to obtain a satisfactory color image.

Example.—Referring now to the drawing, one side of a transparent support is coated with a magenta-dyed green-sensitive silver halide emulsion layer 1 and superimposed on this layer there is a second yellow-dyed, blue-sensitive layer 2. On the other side of the support, there is coated a red-sensitive layer 3 dyed bluegreen and superposed on this is coated a yellow-dyed blue-sensitive layer 4. The whole material thus consists of a support and four layers in three basic colors, one of which, i. e. yellow is present in the opposite surface layers 2 and 4 on both sides of the material. The following dyes 10 may be employed: for the magenta layer Benzopurpurine 10 B (Schultz Farbstofftabellen Leipzig 1931, 7th ed., vol. 1, No. 489) in a concentration of .4 grm. per sq. m.; for the bluegreen layer Pontamine Sky Blue 6 BX (Schultz, loc. cit., No. 510) in a concentration of .5 grm. per sq. m. and for each yellow dyed layer Chrysophenine G (Schultz loc. cit., No. 726) in a concentration of .5 grm. per sq. m. Exposure is effected in a camera provided with a system of 15 mirrors that permits of coincident images being taken from both sides. Cameras of this type are already known, for example from Brewster's U. S. Patent No. 1,253,137 and therefore there is no need to describe them in detail.

20 The material may also be employed as a printing material in order to obtain multicolor pictures by printing. To this end the material is exposed to the multicolor master image, for example in cameras or printing devices of the kind 25 described in the above U. S. patent, one exposure being from one side and the second from the other. White printing light may be used or a colored printing light composed of blue light, green light and red light. These light components 30 may be allowed to act simultaneously or may be used in successive printing operations or for different lengths of time. After exposure, the multilayer film is developed in the usual manner and thereafter the dyes in the layers 35 are destroyed locally, depending on the silver images produced in the emulsion layers. Positive prints are obtained direct from positive master images if the dye is destroyed at the places where silver has been formed by the development, for example by a process of the kind 40

45 50 55

described in U. S. Patent No. 2,020,775 dated November 12, 1935, and granted to Béla Gaspar, to whom the present application has been assigned. A suitable dye-destroying bath is composed, for example of a 5% hydrobromic acid with the addition of .01% 2-hydroxy-3-amino-phenazine.

What is claimed is:

1. A light sensitive material for color photography comprising a transparent support and four superposed light sensitive silver halide layers dyed with dyes which are resistant to ordinary photographic treating solutions but capable of being bleached with the aid of a metallic silver image, two of said emulsion layers being sensitive to blue light and colored yellow, the third being colored magenta and sensitive to green light, the fourth being colored blue-green and sensitive to red light, said magenta colored layer and said blue-green colored layer being arranged between said two yellow colored layers, the arrangement and coloring of the layers forming said material being such that the layers superposed with respect to said magenta colored layer and said blue-green colored layer are transmittant for both green and red light introduced from either side of said material, and the dyes in said magenta colored layer and said blue-green colored layer being sufficient in concentration for natural reproduction of a multicolor image when taken together with the dye in said two yellow colored layers.

2. A light sensitive material for color photography comprising a plurality of superposed silver halide layers each predominantly sensitive to a different portion of the visible spectrum and diffusely dyed complementarily to their respective sensitivities with dyes which are resistant to ordinary photographic treating solutions but capable of being bleached with the aid of a metallic silver image, there being a set of said layers whose combined predominant sensitivities are adapted to record the visible spectrum, and a supplementary layer substantially identical in predominant sensitivity and color with one of said set, the layers of said set other than said last mentioned one being arranged intermediate said last mentioned one and said supplementary layer, the arrangement and coloring of the layers forming said material being such that the layers superposed with respect to said intermediate layers are transmittant for light to which said intermediate layers are sensitive when said light is introduced from either side of said material, and the dyes in each of said colored layers being of such a concentration that when taken in combination with the remaining layers a natural color multicolor image may be produced.

3. A method of making multicolor photographic images in a material comprising a plurality of superposed silver halide layers each predominantly sensitive to a different predetermined portion of the visible spectrum and diffusely dyed complementarily to their respective sensitivities with dyes which are resistant to ordinary photographic treating solutions but capable of being bleached with the aid of a metallic silver image, the dye concentration in at least one of said layers being sufficient for natural reproduction of its corresponding color separation image, which comprises, recording a color separation image in each of said layers from one side of said material, recording in said one

of said layers from the other side of said material the same part image recorded therein by said first recording to intensify the latent silver image obtained by said first recording, developing 5 said images, and destroying the dyestuff in said layers in proportion to said developed silver images.

4. The method of making multicolor photographic images in a light sensitive material including a plurality of superposed silver halide layers each predominantly sensitive to a different portion of the visible spectrum and diffusely dyed complementarily to their respective sensitivities with dyes which are resistant to ordinary photographic treating solutions but capable of being bleached with the aid of a metallic silver image, there being a set of said layers whose combined predominant sensitivities are adapted to record the visible spectrum, and a supplementary layer 10 substantially identical in predominant sensitivity and color with one of said set, the layers of said set other than said last mentioned one being arranged intermediate said last mentioned one and said supplementary layer, the dyes in each of said colored layers being of such a concentration that when taken in combination with the remaining layers a natural color multicolor image may be produced which comprises, exposing said material from one side to form a color separation 15 image in each of the layers of said set, exposing said material from the other side to form a color separation image in said supplementary layer the same as that formed in the layer of said set having the same sensitivity and to form in said intermediate layers additional separation images the same as those already formed therein from the other side of said material, developing said images, and destroying the dyestuff in said layers in proportion to said 20 developed silver images.

5. The method of making multicolor photographic images in a light sensitive material including four superposed light sensitive silver halide layers dyed with dyes which are resistant to ordinary photographic treating solutions but capable of being bleached with the aid of a metallic silver image, two of said emulsion layers being sensitive to blue light and colored yellow, the third being colored magenta and sensitive to green light, the fourth being colored blue-green and sensitive to red light, said magenta colored layer and said blue-green colored layer being arranged between said two yellow colored layers and the dyes therein being sufficient in concentration for natural reproduction of a multicolor image when taken together with the dye in said two yellow colored layers which comprises, exposing said material from one side to form color separation images corresponding to their sensitivity in one of said yellow colored layers and in each of said magenta colored and blue-green colored layers, exposing said material from the other side to form a color separation image corresponding to its sensitivity in the other yellow colored layer and to form in said magenta colored and in said blue-green colored layers additional separation images the same as those already formed therein from the other side of said material, developing said images, and destroying the dyestuff in said layers in proportion to said 25 developed silver images.
